ILLUMINATED WEATHERPROOF WRITING
ACCESSORY

Anita Littrell, Kennewick, Wash.

Application May 20, 1952, Serial No. 288,871

4 Claims. (Cl. 240—6.4)

1

My invention relates to devices which will aid individuals working in railroad yards, policemen, firemen, and checkers of foods and materials, working outside in inclement weather, and those requiring the making of written records in work done outside in snowy, sleety, rainy, or inclement weather.

An important object of my invention is to provide illuminated housing means for supporting a pad or tablet of writing material permitting a hand to be inserted thereinto for holding a writing implement in the operation of writing on the tablet or pad and sealing around the wrist portion of the hand so that moisture, rain and sleet cannot interfere with the writing, thus retaining the interior confines of the writing section of my device free from interference by inclement weather conditions.

Another object of my invention is to provide a writing or housing compartment made up of 20 a base section and a transparent section enclosed by a textile material end section having a constricted opening therein, comprising an elastic element confined within a gathered section of the material so as to permit closure of the same, and distension of the same to admit the hand to the interior of the confines or housing used for protecting a tablet and the writing thereon.

A still further object of my invention is to provide a device of the aforementioned character which is equipped with flashlight means having dual-lighting equipment so as to direct at one of its terminals the lighting within the interior confines of the housing means, and auxiliary lighting means at the other terminal thereof for ordinary flashlight utility and purposes.

A still further object of my invention is to provide spring-urged clip means for retaining a tablet or writing pad removably and interchangeably within the confines of the housing means hereinbefore mentioned.

A still further object of my invention is to provide an article of the aforementioned character which is equipped with intermediate funnel-shaped adapter means permitting removal of the flashlight means for repairs or other purposes that may be required, and interchangeability of flashlights to be used in connection with the rainproof or weatherproof housing means hereinbefore mentioned.

A still further object of my invention is to provide on the flashlight means, used in concert with the weatherproof housing means, arcuately formed ear means to permit the entire device 55 or any other suitable fastening means, and ter-

2

to be held conveniently in one hand, permitting the thumb of the left hand to be inserted through the said arcuate holder means, and permitting the remaining fingers to be wrapped around the cylindrical body of the flashlight; at the same time affording a writing support on the arm of the left hand for the housing means so as to provide a steady and rigid structure to support the right hand in which the writing implement is manipulated.

A still further object of my invention is to provide in a device of the aforementioned character, flashlight means equipped with electrical source of supply means adapted to optionally, or collectively, illuminate either of the plural illuminating means, or both of them simultaneously.

A still further object of my invention is to provide a useful device of the aforementioned character which is simple in construction and economical to manufacture in quantity with proper tools and equipment for the purpose.

Other objects, ancillary advantages and features resident in my invention will become apparent by reference to the accompanying drawings, in which the views are so depicted as to convey to those familiar with the art, the structural details and uses of my invention; the said drawings being further amplified and elucidated in the ensuing description, where like symbols are used to designate like parts, and in which:

Fig. 1 is a perspective view of my invention shown held in the hand and set up for actual use and operation.

Fig. 2 is a cross-sectional view of the flashlight and illuminating structure indicated, which comprises an important element of my invention.

Fig. 3 is an enlarged fragmentary sectional view showing the arm holding arrangement for sealing about the wrist of the hand that is used to manipulate the writing instrument.

Fig. 4 is a fragmentary and enlarged cross-sectional view taken, substantially, on the lines 4—4 of Fig. 1.

Referring to the various views, my invention is generally designated 5; the same being held in the left hand 6 as illustrated, the thumb 7 thereof being inserted through the arcuate loop holding or ear portion designated 45. Thus, the forearm portion of the hand 6 (not shown) affords a rigid support for the base 11 of the weatherproof housing. The said base 11 has mounted thereon, a tapered transparent enclosure 12 suitably secured thereto by cementing, or any other suitable fastening means, and ter-

minating at its end opening which is sealed by a textile closure 27, having an edge section thereof 30 cemented to the transparent casing 12 and to the bottom of the base 11 forming a complete weatherproof enclosure which is accessible to the right hand designated 8, bearing the writing instrument 9 for writing on the tablet or paper unit 10; the same being held in place by virtue of clip 41, being provided with ears 43 and having a frictional gripping terminal portion 44, the same being urged into gripping relationship by virtue of the spring 42 mounted on the pivot 40 and supported by the U-shaped bracket 38 which is fastened to the base 11 by means of a rivet 39 or any other suitable fastening means.

It will be noted that the textile end closure 27 is provided with a restricted arm hole 28, which is expandable by virtue of the gathered portion indicated confining an elastic element therein, so that the same may be expanded to the dotted position 29 indicated which seals around the wrist of the hand 3 so as to prevent rain or the elements from entering the confines; the weatherproof housing hereinbefore mentioned and described.

The transparent element 12 is secured to an adapter element of frusto-conical formation 13, having an integrally formed reflector portion 14 to concentrate the light rays of the illuminating bulb 15 onto the surface of the tablet 10 on which written record is to be made. The said frusto-conical adapter unit 13 is provided with ledges 17 riveted at 16 to the base 11. The partially frusto-conical adapter 13 is provided with a tubular band section 18 in which the flashlight 19 is removably supported. The flashlight is provided with switches 20 and 21 for operating, respectively, the illuminating bulbs or elements 24 and 15.

The interior of the flashlight, at one terminus has a reflector 23 for concentrating the rays of light of the illuminating bulb 24 through the transparent or colored section of the flashlight 22, the end 22 thus being used for flashlight purposes and the other terminus thereof should shed sufficient light on the writing that is to be done.

The switch buttons are provided with extensions 25 and 26 for closing contact with the batteries or sources of supply 32 and 34, the contacts 36 and 37 thereof serving to optionally close the circuits with the illuminating elements 15 and 24, by being grounded to the case 19 of the flashlight and held in contacting relationship with the intermediate spring 33 furnished with electrical contact washers 34 and 35. The battery terminals 36 and 37 being electrically in intimate contact with bulbs 15 and 24.

In actual use the device is held in the left hand 6, the fingers enveloping the body and thumb 7 being inserted into ear 45 so that the base 11 will rest on the forearm to support the writing band 8 for recording on the tablet 10. Illumination 15 and 24 being optional, or lights 15 and 24 may be used individually or in concert dependent on whether switches 20 and/or 21 are actuated to close their respective electrical circuits. The transparent hood 12 protects the writing confines against the elements.

I believe I have herein illustrated and described the nature of my invention, and expounded, in expository form, the teachings so that those familiar with the art will be able to practice my invention.

Having thus disclosed and revealed my invention, what I claim as new and desire to secure by Letters Patent is:

1. A weatherproof writing accessory and flashlight means, comprising a weatherproof enclosure means including a base of substantially triangular configuration, a transparent cover shell made of plastic material and of substantially semi-conical configuration secured to the said base, and a textile end closure secured to the said cover and to the said base defining a writing enclosure shielded from the elements, said end enclosure having an elastic arm hole, a partially funnel shaped adapter element secured to the said base and the said transparent cover, duplex flashlight means having one of its ends secured removably to the said adapter element, and ear means on the said flashlight means for engagement by the thumb of a human hand permitting the fingers to envelop the body of the said flashlight means, the said base resting on the forearm forming a steady rest for writing.

2. A weatherproof writing accessory and flashlight means, comprising a weatherproof enclosure means including a base of substantially triangular configuration, a transparent cover shell made of plastic material and of substantially semi-conical configuration secured to the said base, and a textile end closure secured to the said cover and to the said base defining a writing enclosure shielded from the elements, said end closure having an elastic arm hole, a partially funnel-shaped adapter element secured to the said base and the said transparent cover, duplex flashlight means having one of its ends secured removably to the said adapter element, ear means on the said flashlight means for engagement by the thumb of a human hand permitting the fingers to envelop the body of the said flashlight means, the said base resting on the forearm forming a steady rest for writing, and lamp bulb means at each end of the said duplex flashlight means shedding rays of illumination toward the interior confines of the said weatherproof enclosure means and forwardly and exteriorly of the said enclosure means.

3. A weatherproof writing accessory and flashlight means, comprising a weatherproof enclosure means including a base of substantially triangular configuration, a transparent cover shell made of plastic material and of substantially semi-conical configuration secured to the said base, and a textile end closure secured to the said cover and to the said base defining a writing enclosure shielded from the elements, said end closure having an elastic arm hole, a partially funnel-shaped adapter element secured to the said base and the said transparent cover, duplex flashlight means having one of its ends secured removably to the said adapter element, ear means on the said flashlight means for engagement by the thumb of a human hand permitting the fingers to envelop the body of the said flashlight means, the said base resting on the forearm forming a steady rest for writing, spring-urged clamp means secured to the said base and interiorly of the said weatherproof enclosure means, and writing tablet means releasably held by the said clamp means.

4. A weatherproof writing accessory and flashlight means, comprising a weatherproof enclosure means including a base of substantially triangular configuration, a transparent cover shell made of plastic material and of substan-

tially semi-conical configuration secured to the said base, and a textile end enclosure secured to the said cover and to the said base defining a writing enclosure shielded from the elements, said end closure having an elastic arm hole, a partially funnel-shaped adapter element secured to the said base and the said transparent cover, duplex flashlight means having one of its ends secured removably to the said adapter element, ear means on the said flashlight means for engagement by the thumb of a human hand permitting the fingers to envelop the body of the said flashlight means, the said base resting on the forearm forming a steady rest for writing, lamp bulb means at each end of the said duplex flashlight means shedding rays of illumination toward the interior confines of the said weather-

proof enclosure means and forwardly and exteriorly of the said enclosure means, spring-urged clamp means secured to the said base and interiorly of the said weatherproof enclosure means, and writing tablet means releasably held by the said clamp means.
